(57) **CLAIM**

The ornamental design for an insect repellent cartridge as shown and described.

DESCRIPTION

FIG. 1 is a top, back perspective view of an embodiment of an insect repellent cartridge according to the new design, the portion shown in broken lines forming no part of the claimed design;

FIG. 2 is a bottom, front perspective view of the embodiment of FIG. 1;

FIG. 3 is a front elevation view of the embodiment of FIG. 1;

FIG. 4 is a back elevation view of the embodiment of FIG. 1;

FIG. 5 is a left side elevation view of the embodiment of FIG. 1;

FIG. 6 is a right side elevation view of the embodiment of FIG. 1;

FIG. 7 is a top plan view of the embodiment of FIG. 1; and,

FIG. 8 is a bottom plan view of the embodiment of FIG. 1.
